UNITED STATES PATENT OFFICE.

WALTER A. BEHRENS, OF BROOKLYN, NEW YORK.

MECHANICAL MOVEMENT FOR ELECTRIC SWITCHES, &c.

1,375,247.

Specification of Letters Patent. Patented Apr. 19, 1921.

Application filed December 6, 1919. Serial No. 343,056.

To all whom it may concern:

Be it known that I, WALTER A. BEHRENS, a citizen of the United States of America, residing at Brooklyn, New York, have invented a new and useful Mechanical Movement for Electric Switches, &c., of which the following is a specification.

The main object of my invention is to provide a simple and inexpensive mechanism which can be used to produce a snap action suitable particularly for small switches such as are used in electric sockets.

In its preferred form a swinging member carries a spring which is held under compression by another swinging member adapted to be manually operated. The parts are so proportioned and related that the pressure of the spring is exerted to pull the manually operable member to one side or the other of the pivot of the other member. The initial movement therefore of the operating member merely compresses the spring and moves the fulcrum. The basic idea of the invention may be embodied in a number of different forms of which I have shown six modifications.

Figure 1 is a plan view of one form of mechanism embodying my invention.

Fig. 2 is a side view of the same.

Fig. 3 is a perspective view of one of the swinging members.

Fig. 4 is an end view of the supporting frame.

Fig. 5 is a plan view of a second form of device.

Figs. 6 and 7 are side views of the same showing the parts in two different positions.

Fig. 8 is a perspective view of one of the swinging members.

Fig. 9 is a plan view of a third form.

Fig. 10 is a side view of the same.

Fig. 11 is a perspective view of the compression member of this form of device.

Fig. 12 is a plan view of a fourth form.

Fig. 13 is a side view of the same.

Fig. 14 is a perspective view of one of the transmitting parts of the latter form of device.

Fig. 15 is a plan view of a fifth form of device embodying one form of my invention.

Fig. 16 is a side view and partial section of the same.

Fig. 17 is a plan view of a sixth form of device embodying my invention.

Fig. 18 is a side view of the same.

Fig. 19 is a sectional view on the plane of the line 19—19 of Fig. 17.

The swinging arm 20 is pivoted at 21 to the standard 22. The yoke 23 is pivoted on the same axis and provided with the operating lever or handle 24. The operating compression member 25, has a cross piece 26 in the slot 27, and its ends are pivoted at 28 to the yoke 23. The spring 29 inside of the arm 20, presses against the cross piece 26 and against the abutment 30 so as to yieldingly hold the parts in the position shown in Figs. 1 and 2, the lugs 31 serving as stops for the arms of the member 25, and the shoulder 32 serves as a stop for the arm 20. When the mechanism is used for a switch the parts will usually be supported on an insulating base 33 and provided with one or more contacts 34 and 35 depending upon whether the switch is to be a single or double break mechanism. When the handle 24 is moved downward it carries the hinge connection 28 of the arms of the swinging member 25 past the axis 21 of the member 20 and at the same time increases the compression of the spring 29. When the pivot 28 swings past the pivot 21 the pressure of the spring throws the arm 20 downward with a snap action, the base 33 serving as an abutment for arm 20 and handle 24. When the operating lever or handle 24 is raised the reverse snap action takes place.

In the second form of device shown in Figs. 5 to 8 inclusive the arm 20' and the lever 23' are pivoted on the pin 21'. The link 25' is pivoted at 28' to the lever 23' and has one end 26' bent at right angles and projecting through the slot 27' in the arm 20'. The spring 29' presses at one end against the cross piece 26' and at the other end against the abutment 30' in the arm 20'. When the parts are in the position as shown in Fig. 6 the spring presses the operating member 25' so as to hold the arm 20' and the lever 23' yieldingly in engagement with the base 33'. When the lever is lifted to the position shown in Fig. 7 the arm 20' snaps into engagement with the stop shoulder 32' and the lever 23' strikes against the stop 31'.

In the third form of mechanism illustrated in Figs. 9 to 11 the main arm 20'' is U-shaped and pivoted on the pin 21'' which is carried by the U-shaped support 22''. The lever 23'' is pivoted on the same axis and has one end extended and provided with a

hole to receive the end 28" of the swinging member 25". The other end of the latter member is notched to receive one end of a slide or abutment 26" which is guided in 5 the opposite sides of the arm 20". The other end of the abutment receives the thrust of the spring 29" which is located in one of the side plates in the arm 20". In the position shown, the arm 20" presses 10 against a part of the base 33", and the lever 23" presses against the stop shoulder 36. When the lever 23" is raised the link 25" pushes against the cross piece 26" and compresses the spring until the hinge connection 15 between the lever 23" and the link 25" passes below the pivot 21" whereupon the pressure of the spring is exerted to snap the arm 20" upward away from the base. The upward swinging movement of the arm 20" 20 is limited by the stop shoulder 32", and the upward movement of the lever 23" is limited by the stop shoulder 31".

In the fourth form of mechanism illustrated in Figs. 12 to 14 the arm 20^a and the lever 23^a are both pivoted on the pin 21^a and are connected by a link 22^a one end 26^a of which is bent to form an abutment for 25 the spring 29^a in one side of the arm 20^a and the other end of which is bent to form 30 a hinge connection 28^a with the lever 23^a. In this case a handle 24^a on the shaft 37 is provided to operate the mechanism. The shaft 37 carries a cam 38 formed in two parts with an inclined space between them 35 for the wobbling member 39, one end of which projects through the slot 40 in the supporting frame and engages a notch 41 in one arm of the lever 23^a. When the key handle 24^a is turned approximately 180° in 40 either direction the wobbling lever 39 moves the lever 23^a so as to bring the hinge connection 28^a past the axis of the pin 21^a and allow the spring to snap the arm 20^a. The shoulder 32 serves to limit the upward swing 45 of the arm 20^a, and the base 33^a limits the downward swing of the arm. The wobbling member serves to limit the swing of the lever 23^a. A construction embodying the use 50 of the wobbling member of Figs. 12, 13, and 14 is claimed in my companion application 343,055.

In the fifth form in Figs. 15 to 16, the main arm 20^b is pivoted at 21^b. The operating handle or key 24^b has a shaft 37^b supported in the frame 22^b. The slide 23^b is guided in the frame 22^b and provided with a slot in which the eccentric pin 42 carried by the shaft 37^b operates. The swinging member 25^b is T-shaped and has one end 55 pivoted at 28^b to the slide 23^b and the other end guided in the sides of the arms 20^b where the springs 29^b—29^b are located. The rotation of the key 24^b approximately 180° in either direction shifts the slide 23^b so as 60 to transfer its pivotal connection 28^b from

one side to the other of the axis 21^b and thus cause the springs 29^b to snap the arm 20^b up or down as the case may be. The base 33^b serves as a stop for the arm 20^b in the position shown in Fig. 16, and the shoulders 32^b 70 serve as stops in the upward position.

In the sixth form shown in Figs. 17 to 19, the arm 20^c is pivoted on the shaft 37^c which carries the cam 43 for operating the slide 44. A link 25^c which is hinged at 28^c 75 to the slide 44 is connected at its opposite end to the frame 20^c. A spring 29^c is interposed between one end of the link 25^c and a lug 30^c at one side of the arm 20^c. The spring holds the parts yieldingly in the position of Fig. 18. The arm 20^c presses against the shoulder 32^c or the base depending upon the position of the slide 44. The rotation of the shaft 37^c raises and lowers the slide 44 and shifts the hinge 28^c so as 80 to cause the spring to operate.

I claim:

1. Mechanism of the character described comprising, a pivoted contact arm, a manually movable operating member supported 90 independently thereof, a compression spring carried by said arm and movable therewith and a link pivotally connected to said manually operable member and engaging said arm and spring so as to compress the spring 95 and operate said arm with a snap action when said operating member is moved beyond a certain point.

2. Mechanism of the character described comprising, a pivoted contact arm, a manually operable member, a spring carried by said arm and movable therewith, a link pivotally connected with said manually operable member and having a sliding connection with said arm and engaging said 100 spring to operate the same and move said arm with a snap action when said manually operable member is moved a predetermined distance.

3. Mechanism of the character described 110 comprising, two pivoted members supported independently of each other and having a sliding engagement with each other, a spring carried by one of said members and movable bodily therewith, and a manually operable 115 member pivotally connected with one of said members and supported independently of the other member whereby when said manually operable member is moved a predetermined distance, the said member which is 120 pivoted thereto stresses said spring and moves the other pivoted member with a snap action.

4. Mechanism of the character described, comprising an arm and a lever pivoted on a 125 common axis, a spring carried by and movable bodily with said arm and a link engaging said spring and directly connecting said arm and said lever and stops for said arm and said lever.

5. Mechanism of the character described comprising, a base, a post mounted thereon, a contact arm pivotally carried by said post and having one end movable toward and away from said base, a manually operable member pivotally supported by said post independently of said contact arm having one end movable to and from said base, a link pivotally connected to said manually operable member and having a sliding connection with said contact arm, and a spring interposed between said link and said contact arm whereby when said manually operable member is moved in one direction, it causes said link to apply stress to said spring to move said contact arm with a snap action.
6. A mechanism of the character described, comprising a pivoted tube having a slot therein, a spring mounted within said tube, and movable therewith, a pivoted operating handle and a link hinged to said handle and having a sliding connection with the slot in said tube and engaging said spring to compress the same.
7. A mechanism of the character described, comprising a pivoted tube, a spring contained therein, a lever pivoted on the same axis with said tube, a link pivotally connected at one end to said lever, and at its other end engaging said spring to compress the same.

8. A mechanism of the character described, comprising a pivoted member having a longitudinal slot, a lever pivoted on the same axis with said member, a link pivotally connected to said lever and having a sliding connection in the slot of said pivoted member, and a spring interposed between the axis of said pivoted member and said link whereby the swinging of said lever compresses said spring.

9. A mechanism of the character described, comprising a pivoted member, a U-shaped lever pivotally supported on the same axis as said member on opposite sides thereof, a U-shaped link pivoted to said lever and having a sliding engagement with said member, and a spring interposed between said link and a portion of said member adapted to be compressed when said lever is moved.

10. A mechanism of the character described, comprising a stationary support, a swinging member pivotally carried thereby and having a longitudinally extending slot with an opening at one side, a pivoted operating lever, a link pivoted to said lever and having a sliding connection in said slot, and a compression spring interposed between said link and a portion of said swinging member.

WALTER A. BEHRENS.
